FACE AND EAR SHIELD

Minnie V. Rasmussen, Los Angeles, Calif.

Application June 7, 1947, Serial No. 753,292

4 Claims. (Cl. 2—174)

1

This invention relates to protective devices or shields adapted to be worn about the head by a person having their hair dried under a hot air hair-drying machine for the purpose of shielding the face and ears from the stream of hot air.

I am aware that several head shields have been devised for protecting the wearer while drying the hair under a hot air drying machine, but so far as I know, such devices have not been completely satisfactory. They either fail to give adequate protection, are clumsy to put on and awkward to wear, are not completely disposable, or are difficult to adjust to the individual.

It is an object of this invention to provide a simple shield of the type indicated which does not have the above noted disadvantages.

It is also an object to provide a novel shield of the type indicated adapted to provide ample protection for the face and ears of the wearer against any draft or stream of hot air blowing on the top of the wearer's head.

It is a further object to provide such a shield which can be readily adjusted to fit the particular wearer.

It is a still further object to provide a hair-drying shield which, when worn under the ordinary hot air hair-drying machine, reduces the amount of time required to dry the hair.

It is also an object to provide a shield made of relatively inexpensive readily disposable material so that the same may be used once and thrown away, thereby providing beauty shops and the like with an economical means of affording their customers sanitary protection of the nature indicated above.

These and other objects will be apparent from the drawing and the following description thereof. Referring to the drawing, which is for illustrative purposes only:

Fig. 1 is a side elevation of the device of the invention shown in position on a wearer;

Fig. 2 is a plan view of the device;

Fig. 3 is a sectional elevation on line 3—3 of Fig. 2;

Fig. 4 is a section on line 4—4 of Fig. 2; and

Fig. 5 is a developed view of the device on a slightly smaller scale than the other views.

More particularly describing the invention, reference numeral 11 generally indicates the shield which is shown in Fig. 1 attached to the head of a wearer. The protective device or shield comprises a band-like body of generally oval shape which is preferably formed of a semi-stiff material having some degree of flexibility, such as a paper having this quality. The body of the shield

2

includes generally an elongated curved forward or forehead section 14, a pair of ear sections 15, and a pair of straps 16. The forehead section 14, when flattened (Fig. 5) is generally arcuate. In the normal shape or position of the shield, the forehead section includes a narrow base portion 18 which is substantially vertical relative to a plane passing through the shield, and above this, an upper wider portion 19 which flares upwardly and outwardly from the base portion. As will be apparent from Figs. 1 and 3, only the base portion 18 contacts the head of the wearer, the upper portion 19 extending upwardly and outwardly away from the head of the wearer.

15 The ear sections 15, at the ends of the forehead section, have convexly curved margins 21 and 22 extending laterally beyond the remainder of the shield. The lower portion 23 of each ear section is inclined upwardly and outwardly from its lower margin 21 and the upper portion 24 extends downwardly and outwardly from its upper margin 22. These two portions meet at 25 in a curved section. This construction provides a recess 27 for the reception of the ear, and it will be apparent in this connection that the upper portion of each ear section extends inwardly and over the top of the ear of the wearer when the shield is in place, thereby affording protection against down draft in this region.

20 Extending rearwardly of the ear sections are the straps 16, one of which has been shown shorter than the other, although the relative lengths of the straps are not material. These straps are adapted to extend behind the head of the wearer in overlapping relation and may be adjustably secured together by means of any suitable fastener, such for example, as the well-known bobby pin illustrated at 32, or by a common paper fastener.

25 It will be apparent from the above description and by reference to Fig. 1, that when the device is in place on the head of a wearer, the same fits snugly about the head of the wearer, extending around the upper portion of the forehead and enclosing the ears both at top and bottom and around behind the head of the wearer. The forehead section is inclined somewhat upwardly when viewed from the side with relation to the ear sections and the straps 16 also incline upwardly of the ear sections with the result that the entire device when viewed from the side, presents a very shallow V-shaped form found to be particularly suitable for attachment to the head. At the forehead section of the device, the upper part 19 thereof extends outwardly for a considerable dis-

tance from the forehead of the wearer and thus serves to deflect the downward stream of air away from the face.

It has been found that the use of this device not only serves to shield the face and ears of the wearer but also effects a quicker drying of the hair. The device is thus particularly suitable for persons who cannot stand the higher heat of the hair drier since the use of the shield enables the drying of the hair within a reasonable length of time with the drier at low heat. Heretofore this was not possible.

Although the invention has been particularly shown and described, it is contemplated that various changes and modifications may be made without departing from the invention as defined in the appended claims.

I claim:

1. A shield adapted to be worn about the head to protect the face and ears of the wearer from a draft of hot air from a hair-drying machine or the like, comprising a band-like body formed of flexible, semi-stiff paper adapted to retain its shape, said body having a centrally disposed curved forehead section having a relatively narrow upright base portion adjacent the lower margin adapted to engage the head of a wearer and a relatively wide upwardly and outwardly flared portion above the base portion, a pair of ear sections disposed at the ends of said forehead section, said ear sections each extending laterally beyond the planes of the margins of said forehead section and including a lower portion inclined upwardly and outwardly from its lower margin and an upper inwardly overhanging portion inclined downwardly and outwardly from its upper margin to join said lower portion whereby an ear-receiving recess is formed, and a pair of straps extending rearwardly of said ear sections, said straps being adapted to be disposed in overlapping adjusted relation behind the head of a wearer whereby the same may be secured by a fastener or the like.

2. A device as defined in claim 1 in which the forehead section and the pair of straps are inclined upwardly from the regions where the same join the ear sections.

3. A shield adapted to be worn about the head comprising a band-like body formed of flexible, semi-stiff, paper-like material, said body terminating in a pair of curved straps adapted to be

secured by a fastener or the like in adjusted overlapping relation behind the neck or head of the wearer, said body having a centrally disposed elongated curved forehead section adapted to extend around the forehead of the wearer, said forehead section including a base portion comprising an area of limited lateral extent at its lower margin adapted to fit against the head of the wearer, the remainder of said forehead section being shaped to extend upwardly and away from the base portion and the head of the wearer when worn, and a pair of ear sections positioned between the forehead section and the respective straps, said ear sections each being of greater lateral extent than the remainder of said body and being shaped to provide a lower portion inclined from its lower margin upwardly and outwardly and an upper overhanging portion having a convex margin and being inclined downwardly and outwardly therefrom to said main portion whereby an ear-receiving recess is provided.

4. A shield adapted to be worn about the head comprising a band-like body formed of flexible, semi-stiff, paper-like material, said body terminating in a pair of curved straps adapted to be secured by a fastener or the like in adjusted overlapping relation behind the neck or head of the wearer, said body having a centrally disposed elongated curved forehead section adapted to extend around the forehead of the wearer and upwardly and outwardly thereof, and a pair of ear sections positioned between the forehead section and the respective straps, said ear sections each being of greater lateral extent than the remainder of said body and being shaped to provide a lower portion inclined upwardly and outwardly from its lower margin and an upper inwardly overhanging portion inclined downwardly and outwardly from its upper margin to join said lower portion whereby an ear receiving recess is formed.
